UNITED STATES PATENT OFFICE.

CHARLES E. HEYER, OF CHICAGO, ILLINOIS.

DESIGN FOR A FONT OF PRINTING-TYPE.

SPECIFICATION forming part of Design No. 19,181, dated June 25, 1889.

Application filed May 31, 1889. Serial No. 812,794. Term of patent 14 years.

To all whom it may concern:

- Be it known that I, CHARLES E. HEYER, a citizen of the United States, residing at Chicago, county of Cook, and State of Illinois, have invented and produced a new and original Design for a Font of Printing-Type, of which the following is a specification, reference being had to the accompanying typographical impressions, forming a part thereof.
- 5 This design comprises large initial capitals, small capitals, lower-case letters, dollar-mark, and figures. In general character it is quite ornamental, especially the initial capitals. These initial capitals are designed and adapted to be employed only as initials, and are characterized by three features: First, each letter has either at the top or bottom a horizontal swell-shaded circumflex flourish-stroke extending at considerable length beyond the 10 lateral compass of the remainder of the letter, so that it may overhang or underlie the remaining letters or word with which the initial is associated, except in the case of the letters B, D, I, J, S, X, Y, and Z, which have 15 this flourish-stroke extending to the left; second, the initial capitals are characterized by a fine-line spiral terminal upon one stroke of most of the letters, the inner end of the spiral being slightly swell-shaded; third, the 20 initial capitals have a further characteristic, consisting of a small diamond point placed contiguous to a vertical or within an oval stroke of the letter, the vertical position varying in the different letters.
- 25 The small capitals are characterized by a horizontal circumflex swell-shaded line, which constitutes the characteristic stroke of letters A, E, F, and H, the lower terminal of the oval of B and D, the upper terminal of C and 30 G, the lower terminal of L and S. Another characteristic of the small capitals is a slightly swell-shaded small hook terminating the upper oblique line of K, the initial vertical of M, both the vertical lines of N, the lower end 35 of the oval of P and of the characteristic of 40 R, the upper end of the final stroke of V and W, both ends of one of the strokes of X, the upper end of the final oblique stroke of Y.
- 45 The lower-case letters are characterized by horizontal swell-shaded circumflex lines employed as the cross-stroke of t, the greater portion of the length of said stroke being to the right of the vertical stroke and extending thus to the right a distance about equal to the width of one of the vowel letters, so that 50 in combination with them this cross-stroke overhangs the succeeding vowel. A similar but smaller horizontal circumflex flourish is employed at the upper end of the vertical stroke of the letter d, extending to the left 55 and overhanging the oval of that letter.
- 55 Many of the lower-case letters are marked by the spiral terminal similar to that of the initial capitals above described. Such spiral appears in the tail of g and j, in the upper 60 curve of s, and the lower end of the oval of q.
- 65 I claim—
- 70 The design for a font of type herein shown and described, comprising initial capitals characterized by a horizontal swell-shaded circumflex flourish-stroke as one terminal of each letter, extended considerably beyond the lateral compass of the remainder of the letter, and by fine lines spiral as another terminal of many of the letters, and comprising small 75 capitals characterized by horizontal circumflex swell-shaded stroke as a terminal or characteristic of many of the letters, and comprising lower-case letters, including the letter t, having its cross-stroke consisting of a horizontal circumflex heavily swell-shaded and 80 extended to the right a distance as great as the ordinary width of the letter, substantially as set forth.
- 85 Chicago, May 23, 1889.

CHAS. E. HEYER.
